(57) CLAIM

The ornamental design for a transaction card, as shown and described.

DESCRIPTION

FIG. 1 is a front perspective view of a transaction card showing our new design;

FIG. 2 is a front view thereof;

FIG. 3 is a rear view thereof;

FIG. 4 is a bottom view thereof;

FIG. 5 is a top view thereof;

FIG. 6 is a right side view thereof; and,

FIG. 7 is a left side view thereof.

The features shown in broken lines depict environmental or other associated subject matter and form no part of the claimed design. The bolded dot-dash lines indicate boundaries of the claim, and all other broken lines indicate other unclaimed portions of the design.
